10 which shows a perspective view of the casket.

This design relates to burial-caskets in which the corners are recessed and provided with ornaments, as hereinafter described.

In the illustration, a shows one of the recesses, of which there are four, one in each corner. The recess is curved or concave in cross-section.

15 b b are bevels, one at the bottom and the other at the top of the recess, being highest 20 at the back and presenting an inclined surface to the ends of the recess.

c is an ornament standing in the recess, that shown being a column or pillar.

25 d d are the top and bottom edges or moldings of the casket, which are rounded at the corners and project out beyond the recess, covering the ends of the same and inclosing them, except on the front side, being of full width and contour, as in ordinary caskets of the kind.
